CLAIM

USPC **D9/560**; D9/575

The ornamental design for a fragrance container as shown and described.

(58) **Field of Classification Search**

DESCRIPTION

USPC D9/430-432, 516, 520, 522-524,

Fig. 1.1 is a perspective view of the fragrance container, showing our new design;

D9/528-531, 541-545, 547, 549-551,

D9/553, 555, 558-560, 563, 565-566,

D9/571-575, 682, 686, 687, 693-694,

D9/715, 719; D7/300, 300.1, 316, 317,

D7/598; D23/211, 225; D24/107,

D24/121-123, 216, 217, 219, 223-227

CPC ... B65D 1/00; B65D 1/02; B65D 1/12; B65D

1/18; B65D 1/20; B65D 1/0223; B65D

Fig. 1.2 is a front view of the fragrance container thereof;

Fig. 1.3 is a back view of the fragrance container thereof;

Fig. 1.4 is a right side view of the fragrance container thereof;

Fig. 1.5 is a left side view of the fragrance container thereof;

Fig. 1.6 is a top view of the fragrance container thereof; and,

(Continued)

Fig. 1.7 is a bottom view of the fragrance container thereof. The broken lines shown in Fig. 1.7 depict boundaries of the claimed design that form no part thereof.

1 Claim, 7 Drawing Sheets
